DESIGN FOR A PUNCH

Robert Davol Budlong, Chicago, Ill., assignor to Wilson-Jones Company, Chicago, Ill., a corporation of Massachusetts

Application April 13, 1942, Serial No. 106,564

Term of patent 14 years

To all whom it may concern:

Be it known that I, Robert Davol Budlong, a citizen of the United States, residing at Chicago, Cook County, Illinois, have invented a new, original, and ornamental Design for a Punch, of which the following is a specification, reference being had to the accompanying drawing, forming a part thereof.

I claim:

The ornamental design for a punch, as shown.

ROBERT DAVOL BUDLONG.
